UNITED STATES PATENT OFFICE

94,194

DESIGN FOR A COFFEE MAKING APPARATUS

Frank C. Ehrenreich, Chicago, Ill., assignor to Continental Coffee Company, Chicago, Ill., a corporation of Illinois

Application August 22, 1934, Serial No. 53,019

Term of patent 14 years

To all whom it may concern:

Be it known, that I, Frank C. Ehrenreich, a citizen of the United States, residing at Chicago, in the county of Cook and State of Illinois, have invented a new, original, and ornamental Design for a Coffee Making Apparatus, of which the following is a specification, reference being had to the accompanying drawing, forming part thereof.

The figure is a perspective view of the coffee making apparatus, showing my new design.

I claim:

The ornamental design for a coffee making apparatus, as shown.

FRANK C. EHRENREICH.
